UNITED STATES PATENT OFFICE.

WILLIAM C. MARTINEAU AND CLARENCE R. MARTINEAU, OF ALBANY, NEW YORK,
ASSIGNORS TO PLAYTHINGS CORPORATION, OF ALBANY, NEW YORK, A CORPORA-
TION.

TOY.

1,231,770.

Specification of Letters Patent.

Patented July 3, 1917.

Application filed March 27, 1917. Serial No. 157,666.

To all whom it may concern:

Be it known that we, WILLIAM C. MARTINEAU and CLARENCE R. MARTINEAU, each a citizen of the United States of America, 5 and each residing at the city of Albany, in the county of Albany and State of New York, have invented certain new and useful Improvements in Toys, of which the following is a specification.

10 Our invention relates to toys, and the object of our invention is to provide an ingenious, inexpensive and attractive toy consisting of a novel arrangement for projecting an arrow; together with such other elements and combinations as are hereinafter more particularly set forth.

We accomplish these objects by means of the mechanism illustrated in the accompanying drawing, in which:

20 Figure 1 is a side elevation with the arrow in position.

Fig. 2 is a plan.

Similar letters refer to similar parts throughout the several views.

25 The squared rod, A, is at one end turned or rounded forming a handle, B, and about midway between its ends has an opening, C, therethrough. Through the opening, C, we insert an arrow, D. On each side of the 30 opening, C, are attached the springs, H, H, at the ends of the wire, E. The wire, E, extends parallel and in contact with the surface, a, of the rod, A. The spring may be made, as shown in Figs. 1 and 2, by coiling

35 each end of the wire, E, which wire is bent upon itself at J, at about midway between its ends and driving the end, f, of the wire, after forming the coil, into the rod as shown by dotted lines in Fig. 1. We attach a cord, 40 G, to the portion, J, J, of the spring wires, E, E. The cord is placed in a suitable groove, K, at the end of the arrow, and the

arrow and the cord are drawn in a direction away from the rod, causing the ends of the spring wires, E, to be raised from the surface, a, of the rod against the tension of the springs as shown in Fig. 1. When the arrow is released, after being drawn as above stated, the spring wires, E, E, will forcibly return to the dotted line position and the 50 arrow will be discharged with force from the opening, C.

We do not limit ourselves to the form of spring as illustrated and described.

What we claim as our invention and desire to secure by Letters Patent is:

1. A toy comprising a rod; a handle formed at one end thereof; an opening through the rod for the passage of an arrow; springs having an extended portion, a coil 60 near one end and secured to the rod on opposite sides of but adjacent to said opening, the extended portion normally lying close to the rod, the loose ends of the springs extending in a direction away from the opening; a 65 cord adapted to engage the end of the arrow; said cord attached to the loose ends of the springs, respectively.

2. A toy comprising a rod; a handle formed at one end thereof; a guide for the 70 arrow on said rod; two springs formed of wire attached to the rod, one on each side of said guide, the loose end of each spring extending away from said guide; a cord connecting the loose ends of the springs; with 75 an arrow.

In testimony whereof we have affixed our signatures in the presence of two witnesses.

WILLIAM C. MARTINEAU.
CLARENCE R. MARTINEAU.

Witnesses:

FREDERICK W. CAMERON,
BULAH CARLE.
